M. GOLDSTEIN

WINDOW GUARD

Filed Sept. 24, 1925

UNITED STATES PATENT OFFICE.

MORRIS GOLDSTEIN, OF PITTSBURGH, PENNSYLVANIA.

WINDOW GUARD.

Application filed September 24, 1925. Serial No. 58,317.

My invention relates to improvements in window guards.

An object of the present invention resides in the provision of a window guard mounted for vertical sliding movement with relation to the window pane and adapted to be automatically locked in its lowermost active position, by a novel construction of a lock mechanism carried by the guard, thereby preventing the contents of the window from being stolen should the window pane be broken by anyone with this object in view.

In carrying out the invention I contemplate the use of a manually controlled element for both raising and lowering the guard, and connect said element with the locking arm of the lock mechanism, whereby said arm is moved to a retracted or inactive position to release the guard, simultaneously with the use of the control element for elevating the guard.

Another important object of the invention resides in the fact that the lock casing is carried by the guard and designed to serve in the capacity of a sliding bearing to assist in supporting the guard for vertical adjustment on suitable guides.

Fig. 1 is a fragmentary portion of the guard showing one side thereof, with the lock mechanism;

Fig. 2 is the same of a modified form, the lower section of the guard being shown in lowered and the upper section in an intermediate position.

Referring to said drawings, and particularly to Fig. 1 which illustrates a frame formed of a series of closely arranged, vertically disposed steel or iron rods *a*, the upper and lower ends of which, respectively, are suitably secured in the longitudinally disposed bars *b*, *c*, which extend widthwise of the window, and, with the bars *a* and end side members 1 constitute the frame which forms the guard, which is slidably mounted on the vertically disposed posts 2. Each side member 1 has suitably secured thereto, at a point adjacent the lower end of the guard, an arm 3, the outer ends of which terminate in eyes *d*, which form sliding bearings on the vertically disposed cylindrical rods or posts 2, on which the guard is adapted to be elevated and lowered by a single manually controlled element. This element is preferably in the nature of a cable or rope 4, the outer end of which is connected to the

upper end of the lock bar 5, while the free end of said rope passes over the block 6, which is supported in the ceiling of the window. The frame is adapted to be held in locked position when the same is lowered over the lower section of the window pane by means of the lock mechanism secured to each end of the frame at the extreme upper side thereof. The said lock mechanism comprises a casting 7, which is integral with the side member 1, or is secured to the said side member. There is one of these castings arranged on each side of the guard, and it will be noted that each casting is formed with a cylindrical portion slidably mounted on the adjacent rod 2, so that the casting not only houses the lock mechanism, but is also used in the capacity of a sliding bearing, cooperating with the eye *d* carried by the arm 3 for supporting the guard for vertical sliding movement. In the interior of said casting a lock arm 5, is swingingly or pivotally mounted on the rod *e*, which is secured in the walls of said casting, the lower end of said lock arm terminating in a hooked portion *f*, which is adapted to engage in a correspondingly shaped notch *h* in the outer wall of the casting and also engage the adjacent post to hold the guard locked in its lowermost active position. The said lock arm is held in engagement in said notch by means of the blade spring 8, the free end of which exerts pressure upon the rear side of said lock arm for the purpose of holding the same in engagement with said notch. The upper end of said lock arm is attached to a rope or other flexible connection 4, by pulling which upwardly throws the lower end of the lock arm out of engagement with the notch and permits the lock arm to pass through the slot *k* in the casting and enables the guard to be elevated. Manifestly the lock arm is moved to its inactive position to release the guard, and the latter elevated by one and the same element, namely the cable or rope 4, and these two operations take place practically at the same time by a continued pull on the cable.

In order to lessen the concussion of the frame when the same is lowered, a bumper 9, formed of rubber, is mounted on the support 10, for the purpose of absorbing the shock of the descending frame.

In Fig. 2, I show a modified form of my device in which the guard comprises two

units, one of which comprises the side members 11, to which the ends of the cross bars 12 and 13 are securely fastened; rods 14 being slidably positioned in the bar 12; and the bar 13, similarly positioned on the vertical rods 15, 15. The rods 14, near the top have fastened thereto horizontally disposed bar 16, and near the bottom a bar 17, the said rods 14 being slidably positioned in bars 12, 10 and the rods 15 being slidably mounted on the bar 17, whereby the two units, one comprising the bars 12 and 13, and the side members 11, the other the bars 16 and 17, and the rods 14, may be slidably collapsed 15 or telescoped one against the other when the guard as an entirety is elevated by pulling upon the flexible member or rope whereby the horizontal bars 12 and 16 are brought together and the guard as an entirety is 20 shortened when in an elevated position.

To elevate the structure when the lock arm 18 is disengaged from the notch 19 in the side of the casting 20, by pulling on the rope 21, the guard is caused to move upward on the 25 bearings 22, encircling the posts 23, the upward movement of the side members and the bars 12, 13, ultimately bringing the bar 12 closely against the bar 16, and changing the positions of the bars 13, 17, which have respectively moved upward on the rods 14 and 15. The unit comprising the bars 16 and 17, and the rods 14, are adapted when the structure is in lowered operative position to descend or drop by gravity so that the 30 lower end of the rods 14 rest upon the upper side of the bar 13. It is obvious that an automatic lock mechanism may be provided for the purpose of preventing the upper unit, comprising the bars 16, 17, and rods 14, 35 from being elevated, although even if the

unit was elevated the lower section of the guard is locked when in lowered position, and the rods 15 are sufficiently close to prevent the hand being inserted therebetween.

Having described my invention what I 45 claim and desire to secure by Letters Patent is:

1. In combination, spaced supports, a window guard positioned between said supports, bearings carried by said guard adjacent the 50 lower ends thereof and surrounding said supports, hollow castings carried by the guard adjacent the upper end thereof, and constituting bearings surrounding said supports, whereby the guard is mounted for vertical sliding movements, locking means arranged within said castings and cooperating with the adjacent supports for automatically locking the guard in its lowermost position, and means for elevating said guard 55 when released from said supports.

2. In combination, a window guard mounted for vertical sliding movement, spaced stationary posts supporting said guard, hollow castings carried by the guard 60 and formed to provide bearings slidable on said posts, a cable suspended from an overhead support for raising and lowering said guard, a spring pressed pivoted locking arm arranged in each casting and normally projected therefrom to engage the adjacent post and automatically lock the guard in its lowermost position, and said cable being connected with said arm, whereby the latter is rendered inactive and the guard elevated in 65 cident to a pull on said cable.

In testimony whereof, I have hereunto signed my name.

MORRIS GOLDSTEIN.
